UNITED STATES PATENT OFFICE.

EDWARD SMITH HIGGINS AND HENRY CHARLES JENKINS, OF LONDON,
ENGLAND.

TYPE-WRITING MACHINE.

SPECIFICATION forming part of Letters Patent No. 448,037, dated March 10, 1891.

Application filed July 27, 1889. Serial No. 318,877. (No model.) Patented in England June 6, 1889, No. 9,425.

To all whom it may concern:

Be it known that we, EDWARD SMITH HIGGINS and HENRY CHARLES JENKINS, both subjects of the Queen of England, residing at 5 London, in England, have invented certain new and useful Improvements in Type-Writers, (for which we have received Letters Patent of Great Britain, No. 9,425, dated June 6, 1889,) of which the following is a specification.

This invention, which relates to type-writers, has for its object to simplify the construction of such machines, and has specially among its features to arrange that each letter written 15 shall be apportioned a space proportionate to its requirements—for example, that apportioned to the letter "i" to be less than that apportioned to the letter "n" and that to the letter "n" less than that to the letter "m," and 20 so on. Wherever a particular character requires it, whether such character be a small or capital letter, figure, or punctuation or other mark, a smaller or larger space will be given to it, according to its dimensions.

25 In this specification and claims the word "case" is used to signify a font or set of type characters, the words "lower case" or "stationary case" the font or set normally acted upon by the key-levers, and the words "upper case," "shifting case," or "movable case" 30 that font or set of letters which is normally unacted upon by the key-levers, but which may be operated after depressing a key herein termed the "case-changing key."

35 A machine constructed according to our invention may be provided with a shifting case and a comparatively small key-board by arranging each key to act upon two type characters, or by doubling the number of keys 40 and arranging each to act on one type character the shifting case may be dispensed with.

In the accompanying drawings we have represented only sufficient of a double-case type-writer to enable our invention to be clearly 45 understood.

In the drawings, Figure 1 is a front elevation; Fig. 2, a plan. Fig. 2^a is an enlarged view of the inking-pad and type-guide; Fig. 3, an end elevation; Fig. 4, another plan with 50 the paper-carriage and its adjuncts removed. Fig. 5 is a transverse and Fig. 6 a longi-

tudinal section. Fig. 7 is a view of a blank from which some of our key-levers are advantageously constructed. Fig. 7^a is a plan view of the inner end of a key-lever. Figs. 55 8 and 9 are views of portions of other of the key-levers. Fig. 10 is a view of one of some of the secondary or intermediate levers upon which the key-levers directly act. Figs. 11 and 12 are others of the said levers. Fig. 60 13 is a view of a portion of one of the type-levers, and Fig. 14 a transverse section through a portion of one of the rails on which the type-levers are pivoted. Fig. 15 is a front elevation of a portion of the same and other 65 adjacent parts.

Like letters indicate like parts throughout the drawings.

A' is the stationary frame in or on which are mounted all the working parts of the machine.

B are the key-levers, some of which are preferably stamped out of sheet metal in the form shown in Fig. 7, while others are stamped out to the forms partly shown in Figs. 8 and 9, as 75 hereinafter explained.

From Fig. 7, which by the dotted lines indicates the parts at which the blank is bent to form the finished lever, it will be seen that each key-lever is provided with two platforms 80 b⁴ and b⁵, which are not abreast of each other, and one of which is caused to operate a type-character of the upper case, while when such different printing is desired the other platform is caused to effect the printing of a character of the lower case. The wings b, one of which is connected to the main part of the lever by a neck b⁶, are for preventing the particular intermediate lever C, Figs. 5 and 10 to 12, which each of the key-levers B acts upon, 90 from moving laterally out of the position it occupies relatively to the said lever B.

The configuration of the inner ends of the finished key-levers is illustrated in Figs. 7^a, 8, 9, in which the platforms b⁴ b⁵ and the 95 guide-wings b are shown as bent into their operative positions.

Upon the upper edge of each of the key-levers B is formed a projection b', b², or b³, hereinafter for convenience referred to as the b' 100 projection, b² projection, and the b³ projection. The length of the upper edge of b', as shown

clearly by comparing Fig. 7 with Fig. 8, is shorter than that of b^2 , while that of b^3 , as shown clearly in Figs. 8 and 9, is shorter than that of b^4 , the number of these different lengths (in this example three) corresponding to the number of different letter-spacings which the machine shown on the drawings is adapted automatically to make. This number, as also the number of platforms, such as b^4 b^5 , may be varied to suit the conditions which it is intended each machine shall fulfill. These key-levers B, to stiffen them, are each preferably embossed with one or more longitudinal corrugations similar to the levers T, (see Fig. 6,) and they are all coaxially pivoted on one stationary rod B', supported in the sides of the frame A, the proper distance between the said levers being maintained by collars, bosses, or equivalent means. The forward ends of the key-levers B turn upward, and to the extremity of each of the said upturned ends in the ordinary manner is fixed a button or finger-plate B³, on which is depicted a character which corresponds with the letter or character carried by the type-lever operated by each such key-lever. At these forward ends, also, the key-levers are guided in their vertical movement between pins or wires D, (only one of which is shown in Fig. 5,) which are carried in the bracket-plate D', to which are also secured springs D², the tendency of which is always to raise the forward and lower the rearward ends of the key-levers B.

D³ is a felt, india-rubber, or equivalent buffer, against which strike the key and other similar operating-levers when they return to their normal positions. The before-mentioned secondary or intermediate levers C, upon two of which each key-lever B is adapted to operate, are all coaxially mounted on the same rod C', which is supported in the more downwardly-projecting arm C² of two bell-crank levers, each of which is pivoted at c¹⁰ to one side of the machine. The other arm C³ of each of these bell-crank levers is connected by a link C⁴ to the rear end of one of the two case-changing levers T, which are situated at the sides of the machine, and which, like the other key-levers, are pivoted on the rod B' and turn up at their forward ends, where they are furnished with finger-plates T'. It will therefore be seen that by depressing one of the levers T, by which is meant the forward end of such lever, the rod C', together with all the intermediate levers C pivoted thereon, will be moved forward, C⁵ being a spring which will effect the return to their normal positions of all the parts so moved when the lever T is released by the operator. These levers C, which are generally of the shape shown in Fig. 10, are formed at their rear ends each, preferably, with a slot or recess c, these rear ends, to prevent crowding of the parts connected thereto, being alternately of various lengths, as shown more clearly in Fig. 5. The forward end of each of the levers C is formed with a downwardly-project-

ing heel c² and with an upwardly-extending recess c', the former of which is adapted to rest over one of the platforms b⁴ b⁵—say the platform b⁴—to enable the said lever C to be operated by a key-lever, and the latter is to allow the said key-lever to be depressed without interfering with the lever of the case then out of use, but which lever, when such other case is being used, is over the platform b⁵. Besides the recess c' the neck b⁶ of each lever B is also shaped so as to give ample clearance between the levers B and C by being bent slightly downward, as clearly shown in Figs. 8 and 9. The forward and backward sides c³ of each of the heels c² incline upward in the manner shown in Figs. 10 to 12, so as to enable the said heel to ride up onto one of the platforms b⁴ b⁵ should the said platforms be elevated before the case-changing lever is operated.

Instead of having two platforms b⁴ and b⁵ on the key-lever B and the heels c² all at the same distance from the fulcrum C', it is obvious that we may have a single platform on each lever B and arrange the heels c² of the upper and lower case levers C at different distances from the fulcrum C'.

Where it is desired to apportion to the characters of the movable case greater space than to the corresponding characters of the other case, we provide on each of the levers C which operates such a character a projection or working-face c⁴ or c⁵, the length of the upper edge of the latter of which is greater than that of the former, as shown in Figs. 11 and 12.

To compensate for the loss or gain of motion derived from the irregularity in the lengths of the rear ends of the levers C, the levers connected to their forward or backward ends are formed irregular to secure in themselves an inverse result, which, together with the movements of the said levers C, causes a practically equal amount of motion to be imparted to all the key and type levers. These type-levers E are preferably arranged in two tiers, each consisting of a partly-circular gallery, as shown in Figs. 1, 2, and 5, and each type-lever at its lower end is advantageously formed in the manner shown most clearly in Fig. 13, the length of those of one tier differing from those of the other tier, so that all the types E² may strike at the same point. In Fig. 13, e is a semicircular recess, and e' and e² perforations, the former, as shown in Fig. 5, for receiving the upper end of one of the links F, which connect together the levers C and E, and the other for receiving the upper end of one of the springs E', the lower end of which spring is in any convenient manner fastened to the foot of the standard G', secured to the vertical part A' of the frame A A', which part A' supports the galleries of type-levers. It is by these springs E' that the type-levers E are caused to return to their normal positions when the key-levers are released by the op-

erator. The lower end of each of the type-levers E terminates in a heel e^3 for the purpose of securing it against longitudinal deviation at the time of making an imprinting-stroke, as hereinafter described. The semi-circular recesses e of the type-levers E fit over the rail G, which, besides being curved to the arc of a circle throughout its length, is also partly circular in section. Each of these rails G, of which there are two, one for each tier of type-levers, is formed integrally with the standard G', which is suitably secured to the vertical frame A'. The type-levers E are held apart from each other by the teeth or prongs g of a curved comb-like structure G², which is screwed or otherwise secured to the rail-standard G' in any convenient manner, and one of the said teeth passes between every two type-levers. (See Figs. 2, 5, and 15.) The back or continuous part g' of the comb G² serves as a stop against which the lower or rearward end of each type-lever E strikes when it is caused to make an imprinting action, at which time the heel e^3 projects up at the back of the stop g' and secures the said type-lever against moving longitudinally.

Each of the links F, by which the levers C are connected to the type-levers E, is formed in two parts, which are united by a nut F', screw-threaded right and left handed or otherwise arranged, so as to provide for the effective lengths of such link being adjusted.

The type-levers may, if desired, be formed with embossed corrugations, so as to stiffen them, and when they are drawn back to their normal positions by the springs E' they strike against an india-rubber or equivalent buffer A², so as to prevent undue vibration and noise.

H is the paper-carriage, which in the ordinary manner is capable of being moved in the direction of its length along or across from side to side of the machine in guides A³ in the frame A, J being a barrel containing a spring which, through a chain or the like, (represented in Fig. 6 by a dot-and-dash line j,) always tends to draw the carriage in the direction indicated by the arrow z in Figs. 1, 2, and 6. The power exerted by the last-mentioned spring may, if necessary, be adjusted by winding it up through the media of the square-ended spindle j' (to which one of its ends is connected) and a key, after the manner of winding up a clock, the ratchet and pawl j², Fig. 4, serving to retain the spring against unwinding accidentally.

J' are anti-friction rollers, over which the carriage H rolls, so as to reduce the friction between the said carriage and the guides A³. The carriage H, in the usual manner, carries a paper-roller K, which may be of the ordinary construction, and which is secured fast upon the shaft K', supported in the standards H', which form part of the said carriage. Each of these standards H' is formed with two projecting lugs or bearings h and h', the

former for supporting one end of the rod K², and the latter for supporting one end of the rod K³, the opposite ends of the rods K² and K³ being similarly supported in the standard H' at the opposite end of the carriage. The rod K² is capable of being rotated in the bearings h, and is furnished with a wire loop or frame K⁴, which is adapted to press upon the periphery of the roller K by means of the spring K⁵, one end of which is secured in the rod K² and the other end of which passes beneath the adjacent projecting bearing h, as shown in Fig. 2. On the right-hand end of the rod K² is secured a lever-arm K⁶, by pressing down which the wire frame K⁴ can be moved out of contact with the roller K. The rod K³ is securely fixed in the bearings h', and into this rod, as shown clearly in Fig. 5, are secured the ends of the springs K⁷, the middle portions of which form axles upon which rollers K⁸ are free to rotate, the springs K⁷ holding the said rollers K⁸ in contact with the surface of the roller K.

Upon, preferably, the right-hand end of the shaft K' and outside of the standard H' at that end are secured a milled head K⁹ for enabling the roller to be turned by hand and a ratchet-wheel K¹⁰, with the teeth of which engages a pawl K¹¹, pivoted to a bracket K¹², which is capable of oscillating on the said shaft K' at the inner side of the ratchet-wheel, as shown in Fig. 6. The pawl K¹¹ is formed in part with a handle K¹³, by means of which it may be disengaged by hand from the teeth of the ratchet-wheel K¹⁰, with which it is usually held in engagement by a spring K¹⁴, which is secured to the bracket K¹². This bracket K¹² is slotted or recessed to receive one end of the link L, which is pivoted thereto, and the other end of which link, as shown in Fig. 3, is formed with a slot L', which receives a screw or pin m⁵, by which the said link is jointed to a lever M. The pin m⁵ may be inserted in either of two or more holes m⁶, formed in the lever M, so as to enable the motion imparted to the roller K through the pawl K¹¹ to be adjusted. This lever M is pivoted at m to the adjacent standard H' and at its free or forward end terminates in a handle m', and upon its rearward end acts a spring m², which tends always to draw the said lever into the position in which it is represented in Fig. 3. The upper edge of the lever M is formed with a notch or recess m³ for receiving the projection n, herein-after referred to, and the said lever is also formed with an angularly-shaped slot m⁴ for receiving a projection n'. The projections n and n' are formed on the upper ends of a lever n², pivoted at n³ to the adjacent standard H', this lever, as shown in Fig. 6, forming one end of the swinging escapement-rack N, at the opposite end of which is formed an arm n⁴, by which said rack is pivoted to the adjacent standard H' in a manner similar to that at which it is pivoted at the first-mentioned end. By this arrangement it will be seen that by

depressing the forward end of the lever M the rack N may be moved from the position in which it is shown in full lines to that in which it is shown in dotted lines in Fig. 3, 5 and at the same time the roller K may be moved round upon its axis.

H² is a handle secured to the carriage H and adapted to be used in conjunction with the lever M for moving the said carriage by 10 hand.

O is a shaft supported at its ends in the frame A, and which is capable of being oscillated by a crank-arm O' and other means hereinafter described.

15 O² is a sleeve which is securely fastened to the shaft O and on which is formed an arm O³, the outer end of which, as shown in Fig. 4, is notched or toothed to correspond with the teeth of the rack N. In this sleeve there 20 is secured a "feather" o, over which another sleeve O⁴ is capable of being moved longitudinally, but which feather prevents the sleeve O⁴ from being moved on its axis independently of the sleeve O². On this sleeve O⁴ is 25 also formed an arm O⁵, the outer end of which, like that of the arm O³, is notched to correspond with the rack N, as shown in Figs. 4 and 6. This arm O⁵, as shown clearly in Fig. 5, is slightly wider than the arm O³, and, re- 30 garded longitudinally, the said arms O³ and O⁵ are seen to overlap each other to a small extent. The closed end o' of the sleeve O⁴ fits around and is capable of sliding on the shaft O, and against the inner face of this end 35 bears one end of a spring o², the opposite end of which bears against the sleeve O², so as to tend always to move the sleeve O⁴ in the direction indicated by the arrow y in Fig. 6—that is to say, away from the sleeve O². Be- 40 yond its closed end o' the sleeve O⁴ is reduced in diameter, so as to form a shoulder or face o³, which, like the extreme face o⁴, has a distinct function to perform in the letter-spacing operations, as hereinafter explained. The 45 reduced portion o⁵ is adapted to enter a recess o⁶ of a collar o⁷, secured upon the shaft O, and the effective face of which in Fig. 6 is marked o⁸. The extent of longitudinal motion of which the sleeve O⁴ is capable is limited 50 between the position in which it is shown in Fig. 6—that is, where the arms O³ and O⁵ abut against each other—and the position in which it is represented in Fig. 4, where the faces o³ and o⁸ abut against each other, the 55 reduced portion o⁵ in this last-described position being within the recess o⁶. This maximum amount of motion corresponds to the greatest space which may be given to any one of the printing characters of the machine now 60 being described; but this maximum motion in another machine may be greater or less than in the example here given.

65 P', P², and P³ are three three-sided frames all pivoted on two studs p, one secured into each side of the frame A, as shown in Figs. 3 and 5. The longitudinal member of each of the frames (which members are hereinafter

referred to as the frames P', P², and P³) extend from side to side of the machine, that marked P' passing over all the before-described projections b', b², and b³ of the key-levers B, that marked P² over all the projections b² and b³, but not over the projections b', and that marked P³ over all the projections b³, but not over the projections b' and b² of the said key-levers. At each end the frame P' is formed in one with or secured to an arm p', the free end of which, as shown in Fig. 5, is forked and engages with the pin of the crank-arm O', which, as before described, is 80 secured rigidly upon the shaft O.

p² is a spring, one similar to which is applied to each of the frames P', P², and P³ for drawing it down after the key-levers are released.

85 U is a key-lever, which, like the other key-levers B, is pivoted on the rod B', and the rearward end of which terminates in an upturned projection, the upper edge of which, like one of the projections b², extends beneath the frames P' and P². This key-lever is for blank-spacing, or instead of the blank-spacing being effected by a projection on the lever U, bearing directly against the under side of the frames P' and P², the said lever 90 U may effect such spacing through a lever such as that shown in Figs. 11 and 12, which, however, will not be connected to a type-lever, but will at its forward end be provided with a projection or working-face extending 95 under so many of those of the frames P' P² P³ as may be necessary. In some machines we may altogether omit the projections upon the key-levers B and effect the letter-spacing by the operation of one or more frames—such 100 as P', P², and P³—by projections or working-faces formed on the levers C, so as to operate one, two, or more of such frames. (See Figs. 105 11 and 12.) Instead of having the projections b' b² b³ upon the levers B, the arrangement may be reversed, the projections being 110 upon the frames P' P² P³, and the levers plain.

To each of the frames P² and P³ there is pivoted the lower end of a link p³, the upper end of one of which is jointed to an arm P⁴, 115 that of the other link being jointed to a similar arm P⁵, as shown more clearly in Fig. 4. These arms are adapted to limit the extent of the spaces given to the printing characters by arresting the movement of the sleeve 120 O⁴, as hereinafter explained. The pivot p⁴ of the arms P⁴ P⁵ is carried in a small frame P⁶, which is mounted on guide-rods p⁵, Fig. 4, so that it is capable of being moved vertically up and down. On the pivot p⁴ are also jointed 125 the upper ends of two curved links p⁶, Figs. 4 and 5, the lower ends of these links being pivoted on a bar p⁷, carried in the rear ends of two spacing-key levers p⁸, which are united at their forward ends by a finger-board p⁹.

130 Q is a bracket, which is secured to the base or stationary frame A of the machine in any convenient manner and extends forward over the paper-roller K in the manner indicated in

Figs. 2 and 3. The upper extremity of this bracket is forked to receive the arm Q' , which is pivoted therein, and to the forward end of which is connected the upper extremity of the spring q , the lower extremity of which is secured to a fixed eye q' , the tendency of this spring being always to raise the rear end of the arm Q' . This rear end has a covering or inking-pad q^2 , of suitable material, such as 10 felt or the like, for absorbing a quantity of ink.

Q^2 is a roller of suitable composition or material for distributing the ink over the surface of the pad q^2 , this roller being pivoted on a (preferably) wire spindle q^3 , the ends of 15 which are looped, so that they may be guided vertically on two rods q^4 , which are secured to the bracket Q . Springs or other equivalent means may be employed for increasing the pressure of the roller Q^2 on the inking-pad q^2 .

R is a plate preferably bent to an angle, as shown in Figs. 3 and 5, and which is secured to the bracket Q in any desired manner. This plate, as shown in Fig. 6, is formed with a Y -shaped recess R' , into which each of the type-levers passes when caused to make an imprinting action. The incline-sided mouth r of this recess serves to direct the type-levers into the lower or parallel-sided part r' , in 20 which the type-levers are all in the precise horizontal position for printing, and which serves to lock or secure the said levers against lateral displacement when operated for printing. This parallel-sided part of the recess 25 constitutes the center from which are struck the curves of the galleries on which are pivoted the type-levers. If desired, the plate R may be dispensed with and the lateral locking of the type-carrying ends of the type-levers 30 E may be effected by causing such ends to pass between prongs carried by the free end of the inking-arm Q' , as indicated by dotted lines in Figs. 5, 2, and 2^a.

S is a rod which is secured against longitudinal motion at one end in a lug or bracket s , Figs. 1 and 5, formed on the carriage H , and at its other end in a hole formed in the standard H' at the left-hand side of the machine.

S' is an arm, the position of which may be 45 adjusted on the rod S , and which may be secured in any such position by a binding-screw s' .

S^4 is a spring which holds the arm S' in the position in which it is shown in Fig. 5, a suitable stop being provided to prevent the outer end of said arm from moving to a lower position. The spring s^4 , however, allows the free end of the arm S' to be raised, but returns 55 it to the position shown in Fig. 5 immediately 60 after the cause for its uprising has been removed.

S^2 is the gong which this arm is indirectly caused to sound through the hammer S^3 , which is best represented in dotted lines in 65 Fig. 1. This hammer S^3 is carried on the flexible end s^2 of a lever S^4 , which is pivoted at s^3 , Fig. 1, to the frame A , and on the other

end of which lever the arm S' is adapted to act for operating the said hammer.

S^5 is a spring for throwing the hammer 70 against the gong immediately after the lever is released from the pressure of the arm S' . In its return movement the spring s^4 allows the arm S' to tilt upward when passing across the inclined end of the lever S^4 . 75

The before-described machine may be provided with means for retaining the movable case continuously in action, so as to print, for example, in capital letters only, for any desired length of time. Supposing the machine to be in a normal condition—that is to say, with none of the keys depressed and otherwise ready for work, with the carriage H in its farthest right-hand position and the before-mentioned toothed arm O^5 engaging with the rack N of the escapement and abutting against the arm O^3 —the operation of the said machine may be described as follows: The top edge of the sheet of paper which is to be written upon is inserted between the frame K^4 and the roller K of the said frame by means of the handle K^6 being moved out of contact with the roller. The roller K is then rotated by means of the milled head K^9 , so that the upper edge of the paper is inserted 90 between the rollers K and K^8 . For the convenience of this description let it now be supposed that it is desired to print the letter "i" or some other such letter which requires to be apportioned but a small amount of space. 95 The key-lever B corresponding to that letter is depressed in the usual manner, and through the platform b^4 at the rearward end of the said lever operates the lever C and through it draws down the "i" type-lever. In its descent the type-letter E^2 , carried by this lever E , strikes upon the inking-pad q^2 , which thereby inks the type, but at the same time recedes from the type by the arm Q' turning on its pivot until it is clear of the printing- 100 face of the said type, which then terminates its descent by striking on the paper, and thus printing the letter "i." When the "i" key-lever is released, it is raised by the spring D^2 beneath it and the "i" type-lever E is drawn 105 back to its normal position by its spring E' . So soon as the type-letter E^2 clears the inking-pad q^2 in its upward course the said pad, under the influence of the spring q , moves 110 backward and causes the roller Q^2 to roll over its surface, and thus distribute the ink thereon. Now, as the letter "i" occupies but a minimum amount of space, the key-lever B by which it is operated is provided with a b' projection only—that is to say, one of the 115 projections which are adapted to raise the frame P' only and leave the frames P^2 and P^3 undisturbed. It is therefore only the frame P' which is raised when the "i" key-lever is depressed, with the result that 120 through the forked arm p' , crank o' , and rod O the toothed arm O^5 is tilted backward out of engagement with the rack N ; but just before it is quite so disengaged the toothed arm 125 130

O^3 engages with the said rack, and thus for the time locks it in the position it then occupies. So soon as the teeth of the arm O^6 are clear of the rack N the said arm, under the influence of the spring o^2 , is forced in the direction indicated by the arrow y in Fig. 6 until its progress is arrested by the face o^4 abutting against the arm P^5 , which, as also the arm P^4 , is then laid across the path which extends onward to the collar o^7 . When the "i" key-lever is released and its rearward end thereby allowed to descend, the frame P' , under the influence of one of the before-mentioned springs p^2 , is also caused to descend and at the same time the toothed arm O^3 to be disengaged from the rack N ; but before being quite disengaged the teeth of the arm O^3 are caused to engage with the rack. Immediately after the arm O^3 has been disengaged from the rack N the escapement-spring in the barrel J , overpowering the spring o^2 , draws along carriage H until it is stopped by the arm O^3 , which has been drawn along with it, striking against the arm O^3 , the carriage and the paper having thus been caused to travel to an extent corresponding to what may be termed a "half-letter space." Now, supposing the next letter desired to be written is one which necessitates the apportioning to it of what may be termed a "full-letter space"—such a letter, for example, as "n"—the course pursued, so far as regards the operator, is identically the same as that already described with regard to the writing of the letter "i;" but the key-lever B of this letter "n," instead of being formed with a b' projection, is formed with a b^2 projection—that is to say, a projection adapted to raise both the frames P' and P^2 and leave the frame P^3 undisturbed.

The function performed by the raising of the frame P' in all instances being the same, it is now only necessary to describe how the mechanism is caused to make letter-spaces which shall be greater than those which can be made by the operation of the frame P' . By the operation of, say, the "n" key-lever and the consequent simultaneous uprising of the frames P' and P^2 by the b^2 projection, with which it is provided, the escapement is operated as before; but through the link p^3 , which connects the frame P^2 with the arm P^5 , the said arm P^5 is raised, so that the toothed arm O^5 , under the influence of the spring o^2 , flies toward the collar o^7 and is stopped only when it abuts against the then unraised arm P^4 , which is at the time interposed between the face o^4 and collar o^7 , so that the toothed arm has been carried through one half-letter space (the minimum amount) consequent upon the rising of the frame P' and another half-letter space consequent upon the withdrawal of the half-letter-space-thick arm P^5 from across the path leading to the collar o^7 . Assuming that the next letter or character it is desired to write be one which necessitates the apportionment of what for convenience we term a

"one-and-a-half-letter space"—say, for example, "m"—the operator depresses the particular key-lever corresponding to that character, $7c$ which key-lever, being one of those formed with a b^3 projection, will cause the three frames P' , P^2 , and P^3 to be simultaneously raised, and thus allow the sleeve O^4 , under the influence of the spring o^2 , to move toward the collar o^7 until its travel in that direction is arrested by the face o^3 abutting against the arm P^5 , which, with the arm P^4 , is then elevated into such a position as to allow only the reduced portion o^5 of the sleeve O^4 to move beneath them, both the said arms being at the time interposed between the face o^3 and the collar o^7 . By thus having removed from the path of the sleeve O^4 the two half-letter-space-thick arms P^4 and P^5 the toothed arm O^5 moves toward the right of the machine to the extent of a one-and-a-half-letter space, the distance between the faces o^3 and o^4 being equal to two half-letter spaces, so that as soon as the particular key-lever in operation is released and the arm O^3 consequently disengaged from and the arm O^5 engaged with the rack the escapement-spring in the barrel J will draw the carriage H toward the left of the machine to the said extent. If a character of the stationary case requires, say, a half-letter space, and the corresponding character of the movable case requires, say, a whole-letter space, then the key-lever B of that particular letter is formed with a b' projection for operating only the frame P' , and the lever C , which is adapted to be operated by the platform b^5 of that key-lever, is formed with a projection or face c^4 , which, as shown clearly in Fig. 11, will raise the frame P^2 . If a character of the movable case requires, for example, a one-and-a-half-letter space and the corresponding letter of the stationary case, for example, but a half-letter space, then the particular key-lever B of that character has a b' projection, as before, and the corresponding lever C a c^5 projection or working-face, as shown in Fig. 12. The shifting of the case necessary for making these last-mentioned changes is effected by depressing one of the levers T , so as to move the heels c^2 of one set of the levers C off the platforms b^4 and the heels c^2 of the other set of the said levers C onto the platforms b^5 , in which latter position the said levers C are shown in Fig. 5. It will be seen that should one of the key-levers B be depressed while a change is being made from lower to upper case the forward movement of the inclined sides c^3 of the heel c^2 corresponding to the particular key-lever so depressed by riding up onto the platform b^5 will still cause the particular lever C of the shifting case to be operated and the desired letter to be printed on the paper. Similarly, should any such key-lever be depressed when the case-changing key is released, the rear inclined side b^3 will have a like effect. When the end of a word is reached and it is desired while printing the last letter of the word to

make provision for a space between it and the next to be written, the operator will depress the finger-board p^9 at the front of the machine, and thus, through the rod p^7 and links p^6 , raise the pivot p^4 , which will have the effect of raising the arms P^4 and P^5 clear of the face o^4 of the sleeve O^4 , and thus when a key-lever B is depressed the face o^3 is used in the place of and in a manner similar to the face o^4 , which has been before described, to limit the extent of movement toward the right, the farthermost position of the sleeve O^4 in that direction being that in which the reduced portion o^5 is within the recess o^6 . So soon as the key-levers B and p^8 are released the escapement-spring, as before described, overpowering the spring o^2 , draws along the carriage until it is stopped by the arm O^5 abutting against the arm O^3 , and the pivot p^4 is lowered to its normal position. If spacing without striking a letter is desired, the key-lever U may be repeatedly depressed until the required amount of space is obtained. When the paper being written upon has been moved by the carriage H to the required distance across the machine, which will be announced to the operator by the sounding of the gong S^2 , (the position of the signaling-arm S' having been previously adjusted on the rod S,) the carriage H must be returned to the right-hand side of the machine in order to commence a fresh line of writing. For this purpose the operator grasps the two handles H^2 and m' and presses the latter toward the former, and in so doing first releases the projection n from the recess m^3 , and then by the upper side of the slot m^4 pressing against the projection n' tilts over the rack N into the position indicated in dotted lines in Fig. 3, so as to be clear of the arms O^3 and O^5 , the slot L' being of such length that up to this time no motion has been imparted to the link L. Upon further pressing the handle m' toward the handle H^2 motion is communicated through the link L, pawl K^{11} , and ratchet-wheel K^{10} to the roller K, so that the paper is moved through the distance which has been previously provided for by the particular position which the pin m^5 occupies in the lever M. The operator then, with the handle m' still pressed down, draws the carriage to the right to the desired position for the commencement of another line of printing or writing. The length of the slot L' enables the operator to release the rack N from the arms O^3 and O^5 for moving the carriage across the machine without affecting the line-spacing mechanism, and by the provision of the handle K^{13} the pawl K^{11} may be released from the ratchet-wheel K^{10} , and by means of the milled head K^9 the paper be moved backward or forward through and without affecting other parts of the machine than roller K. The machine may be furnished with guides for suitably conducting the paper to and from the roller K.

Certain of the before-described improvements, in place of being used in a general combination to form a complete type-writer, such as is illustrated in the accompanying drawings, may be applied to type-writers of other construction.

An important feature of the before-described type-writer is that a practically uninterrupted view of the writing as it is produced is always to be had.

Instead of operating the escapement in the manner hereinbefore described, we can arrange it to be operated so that the arm O^3 is normally engaged with the rack N, as is the arm O^5 in the arrangement described, and the arm O^5 will be normally disengaged from but will move along the carriage in the previously-explained manner.

We are aware that it is not new to operate the escapement of the paper-carriage of a type-writer by a frame, such as P', worked by the key-levers, and therefore make no claim to such part individually.

We claim—

1. In a type-writer, a key-lever, a group of secondary levers, a corresponding group of type-levers, and shiftable connections between said levers, whereby the key-lever may be connected with either type-lever of the group, substantially as described.

2. In combination, a key-lever, a group of secondary levers, a movable fulcrum therefore, laterally-extending platforms upon the key-lever, and a heel upon each secondary lever, adapted to ride upon one of the platforms, substantially as described.

3. In a type-writer, a key-lever, a movable group of secondary levers, means for moving the secondary levers to engage any one thereof separately with the key-lever, and a group of type-levers, each type-lever being connected to a secondary lever, substantially as described.

4. In combination, a key-lever having a projection or platform and a secondary lever mounted upon a movable fulcrum and provided with a heel having inclined sides, said heel being adapted to rest upon the said platform, substantially as described.

5. In a variable feed mechanism, a group of frames and a series of key-levers, each bearing a projection, said projections varying in size according to the number of frames desired to be engaged thereby, substantially as described.

6. In combination, a key-lever, a secondary lever operated thereby, and a group of frames forming part of a variable feeding mechanism, said secondary lever having a projection which is adapted to engage selected frames, substantially as described.

7. In combination, a key-lever, a group of secondary levers movably mounted, type-levers, connections between the type-levers and the secondary levers, a variable feeding device, and means for causing the key-lever to

- engage either secondary lever and to produce a corresponding movement of the feeding device, substantially as described.
8. In combination, a key-lever, a feeding device, a secondary lever movably mounted, and means for moving said secondary lever simultaneously into or out of engagement with the key-lever and the feeding device, substantially as described.
10. 9. In combination, a key-lever, a group of type-levers, a variable feeding mechanism, and shiftable connections between said parts, whereby the key-lever may operate either type-lever and cause an appropriate movement of the feeding device, substantially as described.
10. In a type-writer escapement, a rack, two coaxially-mounted arms, each bearing a plurality of teeth, and means for vibrating the arms, substantially as described.
11. In a feeding device, a rack, fixed and sliding coaxially-mounted arms, each bearing a plurality of teeth and adapted to engage the rack, and movable stops for variably limiting the travel of the sliding arm, substantially as described.
12. In a feeding device, a rack, fixed and sliding coaxially-mounted pawls, stepped faces upon the sliding pawl, and a stop movable so as to engage either or neither of the faces, substantially as described.
13. In a type-writer, the combination, with a pivoted ink-pad and types and type-levers for swinging the same, of a distributing-roller arranged to pass over the pad at each of its vibrations.
14. In combination with the supporting bracket, the ink-pad pivoted thereto and normally in the path of the types, the inking-roller, and the guides for said roller, substantially as described.
15. In a type-writer, a pivoted inking-pad forked at its free end, as and for the purpose described.
16. The combination, with the type-lever E, having segmental notch e , of the rail G and comb G², substantially as described.
17. The combination, with the type-levers having notches e and heels e^3 , of the rail G and overlying stop-rail g', substantially as described.
18. The combination, with the line-spacing ratchet and pawl and the operating-lever, of the adjustable link L for varying the line-space, substantially as described.
19. The combination, with the pivoted rack having the projections n and n' , of the lever having the recesses m^3 and m^4 and the spring m^2 , substantially as described.
- In testimony whereof we have hereto set our hands in the presence of the two subscribing witnesses.
